11, 2013, now Pat. No. Des. 781,408.

CLAIM

(51) **LOC (10) Cl.** **23-01**

The ornamental design for a coated screen for large particle
ash control, as shown and described.

(52) **U.S. Cl.**

DESCRIPTION

USPC **D23/386**

Exemplary applications of such coated screen for large
particle ash control are further described in co-pending and
commonly-assigned U.S. patent application Ser. No. 13/633,
717 entitled “Apparatus and Methods for Large Particle Ash
Separation From Flue Gas Using Screens Having Semi-
Elliptical Cylinder Surfaces,” filed Oct. 2, 2012 and issued
Jan. 20, 2015 as U.S. Pat. No. 8,936,662.

(58) **Field of Classification Search**

In addition, the present application is related to U.S. Design
application Ser. No. 29/452,332 entitled “High Surface Area
Ash Removal Screen,” filed Apr. 15, 2013, and issued Feb.
7, 2017 as U.S. D778,423. The disclosures of all applica-
tions mentioned above are incorporated herein by reference
in their entirety.

USPC D23/365, 209, 363, 358, 386, 354, 341,

FIG. 1 is a front perspective view of the coated screen for
large particle ash control;
FIG. 2 is a front elevation view thereof;
FIG. 3 is a back elevation view thereof;
FIG. 4 is a right elevation view thereof;
FIG. 5 is a left elevation view thereof;
FIG. 6 is a top plan view thereof; and,
FIG. 7 is a bottom plan view thereof.
